UNITED STATES PATENT OFFICE

ENOCH J. ASHLEY, OF WATERBURY, CONNECTICUT, ASSIGNOR TO STEELE & JOHNSON
MFG. CO., OF WATERBURY, CONNECTICUT, A CORPORATION

SEPARABLE HOSE CONNECTER

Application filed January 14, 1928. Serial No. 246,702.

This invention relates to improvement in separable hose-connecters and particularly to separable connectors for coupling the hose or tubing of devices, such as washing-machines, dish-washing and other sprays, to faucets.

The object of this invention is to produce a simple, convenient, and leak-proof hose-connecter constructed with particular reference to its adaptability to being attached to faucets of widely-varying types and sizes.

With this object in view, my invention consists in a separable hose-connecter characterized by a faucet-fixture provided with a bore 15 for the reception of the end of a faucet, screw-threads for engagement with a clamping-member, and a plurality of substantially-radial clamping-screws for securing it to the end of the said faucet; a hose-fitting comprising a tubular shank and a sealing-flange; a clamping-member having a bore for the clearance of the said tubular shank, a seat for the said sealing-flange, and screw-threads for engagement with the threads upon the 25 said faucet-fixture; and a resilient washer interposed between the inner face of the sealing-flange of the said hose-fitting and the outer end of the said faucet; whereby, when the said clamping-member is screwed upon the 30 said faucet-member, the said resilient washer will be compressed between the outer end of the faucet and the inner face of the sealing-flange of the said hose-fitting.

My invention further consists in a separable hose-connecter characterized as above and having certain other details of construction and arrangements of parts as will be hereinafter described and particularly recited in the claims.

40 In the accompanying drawings:

Fig. 1 is a view in side elevation of a faucet provided with my improved separable hose-connecter;

Fig. 2 is a broken vertical central section 45 thereof;

Fig. 3 is a broken view in elevation corresponding to Fig. 1, but showing the hose-fitting and clamping-member detached from the faucet-member;

50 Fig. 4 is a detached top or plan view of

the faucet-member of my improved separable hose-connecter;

Fig. 5 is a view thereof, partly in side elevation and partly in vertical section;

Fig. 6 is a detached top or plan view of 55 the hose-fitting of my improved separable connector;

Fig. 7 is a view thereof in side elevation;

Fig. 8 is a detached top or plan view of 60 the clamping-member of my improved separable hose-connecter;

Fig. 9 is a view thereof, partly in side elevation and partly in vertical section; and

Fig. 10 is a detached perspective view of 65 the resilient washer.

In carrying out my invention as herein shown, I employ a sleeve-like faucet-fixture 15 provided near its upper end with three equidistant radially-arranged threaded holes 16 for the reception of an equal number of 70 clamping-screws 17, by means of which it may be secured to the outer end of the spout 18 of a faucet 19. The upper end of the said faucet-fixture is formed at one side with a notch 20 to better clear the horizontal reach 75 of the spout 18 of the faucet 19 aforesaid. The central bore 21 of the faucet-fixture is reduced in diameter at its lower end and provided with internal threads 22 for the purpose as will hereinafter appear. The reduction of the diameter of the lower end of the bore 21 aforesaid, as just above described, results in the production of a guard-shoulder 23 which serves to prevent the outward displacement of a resilient washer 24 of rubber, fiber, 85 or other suitable yielding material.

Seated against the under-face of the washer 24 above mentioned is the washer-like sealing-flange 25 of a hose-fitting, which also comprises a centrally-dependant tubular shank 26. 90 The said shank 26 is attached to the sealing-flange 25 by spinning its inner end 27 over the inner face thereof, so as to crowd the outer face of the said sealing-flange against an outwardly-spun shoulder 28 formed upon the 95 said shank in such manner that the same forms a unitary structure with the flange 25 aforesaid. A hose 29 is sleeved over the tubular shank 26 of the hose-fitting for the purpose of conducting the water from the 100

faucet 19; the extreme lower end of the said shank being provided with a bead 30 to better retain the hose in place.

Before the hose 29 is applied to the tubular shank 26 of the hose-fitting, the said shank is passed downward through an axial clearance-passage 31 smaller in diameter than the adjacent end of the hose 29 and formed in the otherwise closed upper end 32 of a hollow 10 clamping-member 33 which is provided, near its upper end, with external threads 34 for engagement with the internal threads 22 of the faucet-fixture 15 aforesaid. At its lower end the said clamping-member is provided 15 with a laterally-extending annular bead 35, the external periphery of which is knurled, as shown, to facilitate its being screwed in place within the lower end of the faucet-mixture by the fingers of the user.

20 As thus constructed and arranged, the faucet-fixture of my improved separable hose-connector is adapted to be firmly secured to faucets of widely-varying types and sizes by means of the radial screws 17, the diameter 25 of the upper-end bore 21 in the said fixture being designed to accommodate the largest size faucet-spout commonly in use, and the radial screws 17 being relied upon to extend inward sufficiently to engage the said spout, whether 30 the same be round, oval, or of other form.

When it is desired to disconnect the hose 29 from the faucet, it is only necessary to unscrew the clamping-member 33 from the threads 22 of the faucet-fixture 15, whereby 35 the said clamping-member, together with the hose and hose-fitting, may be removed as a unit, leaving the faucet-fixture in place upon the faucet, as shown in Fig. 3 of the drawings, the guard-shoulder 23 of the faucet-fixture at 40 this time acting to prevent the withdrawal of the resilient washer 24 from the faucet-fixture. It will be noted that, owing to the fact that the end of the hose 29 is larger in diameter than the diameter of the clearance- 45 passage 31 in the clamping-member 33, the said clamping-member will be prevented from sliding inward upon the said hose, so that it normally remains in proper place ready for convenient coupling with the 50 faucet-fixture.

It will be noted that when the hose-fitting and clamping-member are assembled with the faucet-fixture and the former firmly screwed into the latter, the inner face of the sealing-flange 25 of the hose-fitting will be forced 55 against the outer face of the resilient washer 24, which, in turn, will have its inner face forced against the lower end of the spout 18 of the faucet 19, so that leakage between the 60 lower end of the said spout and the washer and the inner face of the said flange-member 25 and the outer face of the said washer will be effectively prevented.

I claim:

65 1. As a new article of manufacture a sep-

arable hose-connector comprising a faucet-fixture provided with an axial bore having its lower end formed with internal threads for the reception of a clamping-member and its upper end adapted to receive the terminal of a faucet and provided with an upwardly facing washer-retaining shoulder; means for attaching the said faucet-fixture to the end of a faucet; a hose-fitting comprising a tubular hose-receiving shank and a sealing-flange at the upper end thereof; an inverted cup-shaped externally-threaded clamping-member adapted to be screwed within the said faucet-fixture and having its end-wall formed with a centering passage for the passage of the tubular shank of the said hose-fitting, and providing a seat upon its inner face for said sealing-flange; a resilient washer interposed between the inner face of the sealing-flange of the said hose-fitting and the outer end of the said faucet; and a hose sleeved over the said hose-receiving shank and having its end extended upward into the said inverted cup-shaped clamping-member in position to engage the outer face of the end-wall thereof to limit its axial displacement; whereby, when the said clamping-member is unscrewed from the said faucet-fixture, the said resilient washer will be positively retained on the shoulder in the latter and the said clamping-member will be prevented from sliding inward over the hose by the engagement of the end of the latter with the end-wall of the cup-shaped clamping-member.

2. As a new article of manufacture a separable hose-connector comprising a faucet-fixture provided with means for attaching to it the terminal of a faucet and formed with an axial bore having an upwardly facing washer-retaining shoulder therein; screw threads formed upon the said faucet-fixture for inter-engagement with the threaded portion of a clamping-member; a packing-washer resting upon the upwardly facing shoulder in the said faucet-fixture in position to engage the terminal of a faucet; and a clamping-member carrying a hose-nipple and provided with screw-threads for engagement with the screw-threads upon the said faucet-fixture to force the said packing-washer against the end of a faucet; whereby the said packing-washer is retained in place in the said faucet-fixture in line with the faucet when the said clamping-member is unscrewed therefrom.

In testimony whereof, I have signed this specification.

ENOCH J. ASHLEY.
